HARRY A. LEONARD, OF HOPEDALE, MASSACHUSETTS, ASSIGNOR TO DRAPER CORPORATION, OF HOPEDALE, MASSACHUSETTS, A CORPORATION OF MAINE.

BUILDER MECHANISM FOR YARN WINDING AND SPINNING MACHINES.

Application filed May 20, 1924. Serial No. 714,540.

To all whom it may concern:

Be it known that I, HARRY A. LEONARD, a citizen of the United States, residing at Hopedale, in the county of Worcester and State of Massachusetts, have invented an Improvement in Builder Mechanisms for Yarn Winding and Spinning Machines, of which the following description, in connection with the accompanying drawings, is a specification, like characters on the drawings representing like parts.

This invention relates to yarn winding or spinning machines, and more particularly to the "builder mechanisms" used in such machines for laying yarn upon yarn receivers or bobbins.

In winding yarn upon yarn receivers or bobbins which are to be used in so called "feeler looms" it is desirable to preliminarily wind upon the yarn receivers or bobbins sufficient yarn to insure the laying of a complete length of filling in the shed on the final pick of the shuttle prior to replenishment.

These preliminary windings are frequently referred to as "bunches" and are designed to cooperate with the feeler in filling replenishment or feeler looms to call for a change in filling when that in the active shuttle has become substantially exhausted.

Many varieties of mechanisms have heretofore been suggested for placing such preliminary windings or bunches upon the bobbins before commencing the regular windings, but these have been of complicated construction and not readily applicable to the ordinary builder mechanism which usually consists of a builder cam and a builder arm connected by a flexible chain or strap to the yarn guiding means.

One of the objects of the present invention is to provide a bunch builder mechanism which may be associated readily with a builder mechanism of usual construction now in common use without any material alteration thereof and wherein the bunch builder is of simple construction.

When a set of yarn receivers or bobbins have been fully wound with yarn, it is now the common practice to stop the machine for

doffing, that is, to replace the full bobbins with empty ones prior to again commencing the winding operation, and an important feature of the present invention therefore consists of means associated with the regular builder arm for throwing into action the bunch builder mechanism prior to starting the machine after doffing, and automatically render the bunch builder mechanism inoperative when the bunch has been completed to lay the regular traverse of yarn on the yarn receivers or bobbins to complete the windings.

The various novel features and new combination of parts comprised by the present invention will best be made clear from the following description and the accompanying drawings of one good practical form thereof, it being understood that the details may be varied within the true scope of the invention as defined by the claims. The invention will conveniently be described in connection with an ordinary spinning machine wherein the yarn is spun and then wound upon the receivers or bobbins, but the invention is obviously not restricted to use with such machines but may be advantageously employed in connection with other types of yarn winding machines.

In the drawings:

Fig. 1 is a perspective view of a machine containing the present invention, some of the parts of the machine being omitted for the purpose of clearness of illustration;

Fig. 2 is a side elevation, some of the parts being shown in section, of a builder motion containing the present invention;

Fig. 3 is a plan view;

Fig. 4 is a front view of the builder arm and bunch builder on an enlarged scale, some of the parts being shown in section; and

Fig. 5 is a cross-section on the line 5—5 of Fig. 3.

The invention is shown as applied to the builder mechanism of an ordinary spinning machine of the usual type whereby the yarn is spun and wound directly upon yarn receivers or bobbins, but it has not been

deemed necessary to illustrate the entire spinning machine except in so far as the present invention is associated with the details thereof, because such machines are now well known.

The end frames 1 of the machine, Fig. 1, are connected by the usual cross-ties 2, and the spindle rail 3 on which the spindles 4 are mounted for rotative movement, as usual. The ring rail 5 extends longitudinally of the machine and is provided with a series of rings 6, one only being shown in Fig. 1, and on each of the rings 6 is a traveler 7 by which the yarn is directed to the yarn receivers or bobbins mounted upon the rotating spindles.

Extending from the frame of the machine, as shown, from the cross-piece 2 is a bracket 8 on which is mounted a rock shaft 9 having an arm 10 on the end of which rests a shoe 11 of the ring rail lifter rods 12 whereby as the rock shaft 9 is rocked, the ring rail would be given its traversing movements longitudinally of the yarn receivers or bobbins. The rock shaft 9 is provided with an arm 13 carrying a weight 14 which normally tends to impart a lifting movement to the ring rail, as usual.

Secured to the rock shaft 9 is the segment 30 arm 15 having connected thereto the flexible member or chain 16 which extends over a guide-pulley 17 mounted on a bracket 18 carried by the machine frame and from thence downward to the builder arm 19 where the flexible member or chain 16 is secured to the usual drum 20 mounted for rotative movement upon the builder arm.

The drum 20 has associated therewith the worm wheel 21 which engages a worm 22 mounted as usual on the builder arm and actuated by the pick wheel 23 as the builder arm is raised and lowered. In the present instance, the pick wheel 23 is given its step-by-step movement by a pawl 24 mounted on the rocking arm 25 connected at one end to a fixed part of the machine frame by means of a rod 26. The builder arm 19 carries a pin or roller 27 which during regular traverse engages the periphery of the main traverse cam 28. The builder arm 19 is mounted for rocking movement about a center 29, the construction being such that during regular traverse of the builder mechanism, the builder arm will be raised and lowered by the combined action of the weight 14 and the main traverse cam 28 to lay the yarn upon the yarn receivers or bobbins by regular traverse, and during such movement of the builder arm the pick wheel is actuated to let back on the flexible member or chain 16, thereby laying the yarn upon the yarn receivers with a traverse that gradually approaches the top or end portions of the yarn receivers or bobbins. The mechanism so far described may be of usual con-

struction and is well understood by those familiar with builder mechanisms.

In accordance with the present invention, the bunch builder comprises coacting elements which may be brought into cooperative relation for building the bunch under manual control of the machine attendant, and then automatically moved out of coacting relation when the bunch is completed to permit the main traverse winds to be laid upon the yarn receivers or bobbins without a jump being introduced between the completion of the bunch and the commencement of the main service wind. The main portions of the bunch builder coacting members are mounted upon the builder arm and comprise a cam, shown as on the builder arm, movable to and from operative position, and such main portions of the bunch builder are constructed and arranged so that they may be applied to the regular builder arm now in ordinary use without material change in the details thereof.

Mounted upon the builder arm 19 is a frame 30 which may be appropriately secured to the builder arm by any approved or usual means, and at each end of the frame 30 are the laterally projecting bearings 31 which afford support for a worm shaft 32 carrying a worm 33, Fig. 2. As shown, the worm shaft 32 is journaled in bearings in the portions 31 of the frame and the worm 33 is disposed between such bearings. Secured to one end of the worm shaft 32 is a bevelled gear 34 which meshes with the corresponding bevelled gear 35, the latter of which is mounted on the axial support 29 of the builder arm 19 and is continuously driven from any suitable source by a train of mechanism, which in the present instance comprises the sprocket chain 36 which passes about a sprocket wheel on the axial support or shaft 29 and about another sprocket wheel 37 mounted on a shaft 38 carried by a cross-member 39 of the machine frame. On the shaft 38 is a similar sprocket wheel 40 about which passes the sprocket chain 41 which derives its motion from the sprocket wheel 42 mounted on the main traverse cam shaft 43, the construction being such that as the main traverse cam 28 is rotated, as usual, from a going part of the machine, the worm shaft will be continuously rotated. In order that the slack in the sprocket chain 41 may be taken up and the chain held taut and in operative relation with its coacting parts, the sprocket chain 41 passes over the idler or tightener 44 mounted on the machine frame or part 39 by means of an arm 45. The sprocket chain and sprocket wheel train of mechanism affords a good practical form for transmission of power to the worm shaft 32, but obviously, the worm shaft may be driven from any suitable source of power.

5 Mounted between the bearing brackets 31 of the frame 30 of the bunch builder is a cam carrier 46 normally under the influence of a spring 47 tending to move the cam carrier to its operative or cooperating relation with the other member of the bunch builder. As shown, in the present instance of the invention, such other member of the bunch builder comprises a roll 48 which 10 may be conveniently mounted in fixed position by means of a bracket 49 extending downwardly from the cross member 39, Fig. 2.

15 The cam carrier 46 is guided in its movements between the bearing members 31 of the bunch builder frame by the guide rod 50 and such carrier has an opening through which passes the worm and worm shaft 32, as shown in Fig. 2. Mounted upon the cam 20 carrier 46 is the bunch builder cam 51, the contour of which, as indicated at 52, is such that it may cooperate with the bunch builder member 48 during the bunch building operation to form the bunch of suitable shape and 25 appropriate number of winds, before the bunch builder mechanism passes into position of inactivity. In the present instance of the invention, the bunch builder cam 51 is detachably secured to the carrier 46 as by 30 means of the screws 53, although, as will be evident, the bunch builder cam may be formed integral with the carrier.

35 In accordance with the present invention, the bunch builder cam on the builder arm 40 may be rendered effective to build the bunch under manual control of the machine attendant, and to this end there is mounted on the builder arm, and preferably on the stud 54, a treadle 55 which has connected thereto a downwardly extending portion 56 normally bearing against the front end portion 45 of a trip 57, the purpose of which is to trip the bunch builder cam on the bunch builder arm and permit it to move to cooperative relation with the fixed member 48 of the bunch builder, under control of the machine attendant.

50 The trip 57 may be variously contrived, but in the present instance of the invention it is shown as a bar extending longitudinally of the builder arm and connected to the frame 30 by the pins 58 which enter diagonal slots 59 formed in the trip bar 57, the effect being that when the treadle 55 is depressed, 55 the trip bar 57 will be moved rearwardly, as shown, and laterally, for the purpose of freeing the bunch builder cam for movement to its bunch builder position, as will now be explained. Mounted upon the cam carrier 46 and movable therewith is a worm engaging member or catch 60 which, as shown in Fig. 5, passes through an opening in the carrier 46 and has the upturned end portion 61 formed with a lug 62 for engagement with the worm 33. The catch 60 is

5 normally under the influence of a spring 63 which may be interposed between the carrier 46 and a collar 64 secured to the laterally projecting portion of the catch 60 and normally acting to throw the catch into cooperative relation with the worm. As indicated in Fig. 5, the worm engaging end 62 of the catch passes through an opening in the carrier 46 so that when the end 62 of the catch is engaged with the worm, the bunch builder 10 cam will be gradually moved from the operating position to which it has been previously moved by the spring 47 to its inoperative position, or rearwardly, as shown, and during such movement of the bunch builder cam, the collar 64 on the catch 60 will move along the upturned edge portion 65 on the trip arm 57.

15 When the bunch builder cam 51 has been moved rearwardly to its inoperative position, it is desirable that it be locked in such position until, under the dictates of the machine attendant, the catch 60 may be manipulated to free the cam for movement to its operative position under control of the spring 47. In the present instance of the invention, the cam shaft 32 at the rear portion thereof is provided with a recess 66, Fig. 2, and when the active end 62 of the catch 60 has been moved to carry the bunch builder cam 51 to its inactive position, the end 62 of the catch will engage the recess 66 at the end of the worm and lock the bunch builder cam in its inoperative position 20 where it will remain during the regular 25 traverse.

30 Assuming that a series of carriers or bobbins have been completely wound and are ready for doffing, the machine attendant may place his foot on the treadle 55 to first trip the catch 60 from the recess 66 in the worm shaft, thereby unlocking the bunch builder cam for movement to its operative position, to the left, under the impulse of the spring 47, and second, to lower the ring rail for doffing, and when the attendant removes his foot from the treadle 55, the catch 60 will move to operative relation with the worm, so that on starting the machine again 35 the bunch or preliminary windings will first be placed upon the filling carriers or bobbins. During the bunch building operation the cam 51 will consequently be moved by the worm towards its inoperative position, and when the bunch is completed will finally move out of cooperative relation with the member 48 of the bunch builder, at which time the end 62 of the catch will engage the recess 66 in the worm and lock the bunch builder cam in its inoperative position, to permit the yarn to be laid upon the carriers or bobbins with regular service wind, as usual.

40 It will be noted that when the members of the bunch builder are in cooperative re-

- lation, the builder arm is entirely under the control of the bunch builder members, and as the bunch approaches completion the form of the bunch builder cam and its relation with the main traverse cam is such that the main traverse cam will take control of the builder arm through the roll or pin 27 without any jump of the ring rail, thereby avoiding the breaking of ends.
- 10 The character and shape or size of the bunch during the bunch building operation is entirely under the control of the bunch builder cam on the builder arm, and its co-acting member 48, and by varying the contour of the bunch builder cam, any desired character or form of bunch may be wound. In order to vary the size of the bunch made by the bunch builder cam, the present invention contemplates means for limiting the 15 amplitude of movement of the bunch builder cam as it travels back to its operative position as the operative trips the catch through the treadle 55. In the present instance, such movement of the bunch builder cam to its 20 operative position may be regulated by means of an adjusting bolt 67 which may be conveniently threaded through the front bearing member 31, as indicated in Figs. 2, 3 and 4, and extend inwardly to contact with 25 the carrier 46 and limit its movement to operative position. To prevent accidental displacement of the regulating device 67, the latter may be provided with a set nut 68 to maintain it in adjusted position.
- 30 During the bunch building operation, the contour of the bunch builder cam 51 will dictate the character of the bunch, so that by changing the contour of the bunch builder cam the bunch may be given one or 35 more travels to complete the bunch, and at the end of the bunch building operation the bunch builder cam will automatically move out of operating relation with its coacting member 48 and regular 40 traverse. It will be assumed without jump of the ring rail. From the construction described it will be apparent, also, that the bunch builder of the present invention may be conveniently applied to the ordinary builder 45 mechanisms now in common use without materially altering the construction or details thereof; by simply applying to the bunch builder arm the associated elements of the bunch builder cam and driving connections between the worm of the bunch 50 builder mechanism and a going part of the machine.
- 55 It is sometimes desirable to give a slight movement to the ring rail, called "jig- 60 gling", before commencing the formation of the bunch, or at any other stage of the winding operation, and in the present instance of the invention, instead of the attendant placing his foot upon the treadle 65 55 in depressing the ring rail for doffing, he

may place his foot upon the builder arm or upon the arm 10 to depress the ring rail and impart the jiggling movement to the yarn guides or ring rail and thereafter operate the treadle for throwing the bunch builder 70 mechanism into operation.

The trip bar 57 may ordinarily be returned to its initial position by the spring 63 of the worm engaging catch, but if desired the arm 57 may be assisted in this 75 movement by a spring such as 57*.

What is claimed is:

Claims.

1. In a builder mechanism, the combination of yarn guides for directing yarn to 80 yarn receivers, a builder arm and regular traverse cam, connections between the builder arm and yarn guides, a bunch builder member mounted on the builder arm and normally maintained in an inoperative position, a manually operated trip mounted on the builder arm for releasing the bunch builder member that it may move to bunch builder position, and means for automatically returning the bunch builder member to inoperative position on completion of the bunch. 85

2. In a builder mechanism, the combination of yarn guides for directing yarn to 90 yarn receivers, a builder arm and regular service cam, connections between the builder arm and yarn guides, a bunch builder cam mounted on the builder arm for movements to and from operative position, a member connecting with the cam on the builder arm for building the bunch, and means for moving the bunch builder cam on the builder arm out of coacting relation with said member when the bunch is completed that the 95 yarn may be laid upon the receivers thereafter with regular service traverse. 100

3. In a machine for winding yarn upon 105 yarn receivers, the combination of a main traverse cam and builder arm actuated thereby to lay the yarn upon the receivers with main service traverse, and a bunch builder mechanism for laying the preliminary windings on the receivers, comprising a bunch builder member mounted on and for movement lengthwise of the builder arm, means for holding the bunch builder element in inoperative position during the winding with main service traverse, a manually operated trip mounted on the builder arm for freeing the bunch builder element for movement 110 lengthwise of the builder arm into operative position, a second bunch builder element coacting with the member on the builder arm during the bunch building operation, and means for automatically disengaging 115 said members when the bunch is completed. 120

4. In a machine of the character described, the combination of a main traverse cam and builder arm, a bunch builder cam mounted on the builder arm, a member coacting therewith to build a bunch, means normally tend- 130

ing to move said members relatively into cooperative relation, a treadle mounted on the builder arm, a trip actuated by manual operation of the treadle to permit the bunch builder members to assume cooperative relation, and means on the builder arm for automatically moving the builder members relatively into inoperative relation.

5. In a machine of the character described, 10 the combination of a main traverse cam, a builder arm, a bunch builder cam mounted on the builder arm, a bunch builder member coacting with said cam on the builder arm to build a bunch, a treadle mounted on the 15 builder arm, a train of mechanism controlled by the treadle for effecting movement of the bunch builder cam and bunch builder member into cooperative relation when the treadle is manually actuated, and means for 20 moving the bunch builder cam and said member into inoperative relation when the bunch is completed.

6. In a machine of the character described, 25 the combination of a main traverse cam, a builder arm, a bunch builder cam mounted on the builder arm, a bunch builder member coacting with said cam on the builder arm to build a bunch, a treadle mounted on the builder arm, a train of mechanism controlled 30 by the treadle for effecting movement of the bunch builder cam and bunch builder member into cooperative relation when the treadle is manually actuated, a device for regulating the extent of said movement to 35 determine the size of the bunch, and means for moving the bunch builder cam and said member into inoperative relation when the bunch is completed.

7. In a machine of the character described, 40 the combination of a main traverse cam, a builder arm, yarn guides connected to and traversed by the builder arm, a bunch builder cam mounted upon the builder arm, a bunch builder member mounted for cooperating 45 with the bunch builder cam on the builder arm to build a bunch, means for effecting movement of the bunch builder cam on the builder arm into cooperative relation with the bunch builder member, and treadle 50 means on the builder arm for controlling movement of the bunch builder cam on the builder arm.

8. In a machine of the character described, 55 the combination of a main traverse cam, a builder arm, yarn guides connected to and traversed by the builder arm, a bunch builder cam mounted upon the builder arm, a bunch builder member for cooperating with the bunch builder cam on the builder arm to 60 build a bunch, a worm on the builder arm, means for turning the worm, a carrier for the bunch builder cam, and means for causing the carrier to be actuated by the worm and to be moved by it to place the bunch 65 builder cam in its inactive position.

9. A bunch builder, comprising, in combination a builder arm and connected yarn guides, coacting elements adapted to wind a bunch on yarn receivers, treadle controlled means mounted on the builder arm to move 70 said coacting elements relatively into operative relation controlling the builder arm, and automatic means for returning said coacting elements into inoperative relationship that service windings may be laid upon the 75 yarn receivers.

10. A bunch builder, comprising, in combination a builder arm and connected yarn guides, coacting elements adapted to wind a bunch on yarn receivers, treadle controlled 80 means mounted on the builder arm to move said coacting elements relatively into operative relation controlling the builder arm, a regulator for determining the amount of relative movement of the coacting elements, 85 and automatic means for returning said coacting elements into inoperative relationship that service windings may be laid upon the yarn receivers.

11. In a machine of the character described, the combination of a builder cam, a builder arm, yarn guides connected to the builder arm, coacting elements adapted to be brought into engagement to build a bunch, treadle controlled means mounted on 90 the builder arm to cause said elements to be brought into engagement by manual operation of the treadle relative to the builder arm, and means for disengaging said elements when the bunch is completed.

12. In a builder mechanism, the combination of a builder cam, a builder arm, coacting members adapted to actuate the builder arm to effect winding of a bunch, one of said members being mounted in fixed position 105 and the other movable longitudinally along the builder arm, a worm mounted on the builder arm for moving said other member during the formation of the bunch, means for locking said other member in an inoperative position when the bunch is completed, and a trip mounted on the builder arm for freeing said other member for actuation by the worm to commence winding a bunch 110 when the machine is started after doffing.

13. In a builder mechanism, the combination of a builder cam, a builder arm, coacting members adapted to actuate the builder arm to effect winding of a bunch, one of said members being mounted in fixed position 120 and the other movable longitudinally along the builder arm, a worm mounted on the builder arm for moving said other member during the formation of the bunch, means for locking said other member in an inoperative position when the bunch is completed, a spring for returning the said other member to operative relation with its coacting member, and a trip mounted on the builder arm for freeing said other member for actu- 125 130

ation by the worm to commence winding a bunch when the machine is started after doffing.

14. A bunch builder, comprising, in combination, a builder arm and connected yarn guides, coacting members for controlling the movements of the builder arm for winding a bunch, one of which is a cam mounted upon the builder arm, and treadle controlled

means mounted on the builder arm for placing the cam on the builder arm in cooperative relation with its coacting member for automatically winding the bunch when the machine is started after doffing.

In testimony whereof, I have signed my name to this specification.

HARRY A. LEONARD.
